UNITED STATES PATENT OFFICE.

WILLIS S. FARNSWORTH AND WILLIAM H. REED, OF PETALUMA, CALIFORNIA, ASSIGNEES TO COIN CONTROLLED LOCK CO., OF PETALUMA, CALIFORNIA, A CORPORATION OF CALIFORNIA.

MAGAZINE-HINGE AND CONVEYER.

985,990.

Specification of Letters Patent. Patented Mar. 7, 1911.

Application filed June 1, 1910. Serial No. 564,418.

To all whom it may concern:

Be it known that we, WILLIS S. FARNSWORTH and WILLIAM H. REED, both citizens of the United States, residing at Petaluma, in the county of Sonoma and State of California, have invented new and useful Improvements in Magazine-Hinges and Conveyers, of which the following is a specification.

10 This invention relates to a hinge, and particularly pertains to a combined hinge conveyor and coin magazine or till.

15 It is the object of this invention to provide a mechanism which is adapted to serve both as a hinge and as a coin conveyer and magazine, and which is particularly applicable for use on cabinets, lockers and the like in which coin-controlled means are employed in operating the locks of the hinged doors.

20 A further object is to provide a hollow hinge to serve as a coin conveyer where several doors are adapted to be mounted in series, so as to provide a continuous tubular coin conveyer of any length and for any 25 number of separately hinged doors, by which the coins of a great number of lock-controlling devices may be all gathered into one receptacle.

30 Another object is to provide a hollow hinge of this character which is simple in construction, efficient in operation, and which can be readily applied.

35 The invention consists of the parts and the construction and combination of parts as hereinafter more fully described and claimed, having reference to the accompanying drawings, in which—

40 Figure 1 is a front view of a series of lockers, showing the invention as applied. Fig. 2 is a detailed view in elevation of a portion of the conveyer hinge, with parts broken away. Fig. 3 is a sectional view on the line X—X, Fig. 2. Fig. 4 is a section 45 on the line Y—Y, Fig. 2.

45 In the drawings, A represents a door, or a series of doors, which may be of any suitable description and which may be hung in any desired casing B, here shown as a cabinet containing a series of lockers. Each door A has secured to its rear or hinge edge a tube or cylinder 2, the ends of which project a short distance above and below the top and bottom of the door and form pintles on

which the door turns. The tube 2 is secured 55 to its door A by suitable means, as screws 3 which are screwed into the door from inside the tube 2, an opening 4 being provided in the tube 2 opposite the screw 3 through which the screw and a screw-driver may be 60 inserted. Each door is hung by the straps or bands 5 which are placed over each of the projecting ends of the tube 2 and are secured to the casing B by screws or other suitable means. Where several doors are 65 placed one above the other, as shown in Fig. 1, each hinge strap 5 has a rib 6 formed on the inner side of the strap, against which rib an end of a tube 2 abuts or rests. Thus for each door, one-half of its lower strap 70 with its rib 6 supports the tube 2 of that door, while the lower half of the same strap supports the upper end of the tube below and retains it in a vertical position. Where a number of doors A are mounted one above 75 the other, as shown in Fig. 1, one strap 5 will serve to support the tube above and to retain the one below in alinement therewith. In this manner a hollow, continuous, sectional tube is formed extending from the 80 uppermost locker door A to the floor or bottom of the cabinet.

Each door A is provided with a coin slot 7 and a coin chute 8, the latter terminating in a slot 9 formed in the tube 2; it being 85 understood that each door is normally locked by a suitable coin-controlled lock, represented at 10, and that the coin which is dropped into slot 7 and finally finds its way to the hinge-conveyer-tube 2 operates to unlock the lock in any well-known manner.

90 The operation of the invention is as follows: A coin being dropped in the slot 7 in the door A, operates any desired mechanism, and after performing a required function 95 passes on down the chute 8 and enters the vertically disposed tube 2, down which it falls and is conveyed to any suitable coin receptacle.

90 By this construction, one common receptacle or cash drawer 10 may be provided for a large number of lockers, chutes 11 connecting each bottom terminal of a vertical line of conveyer tubes 2 with the cash receptacle or till 10.

100 If desired, each tube 2 may be provided with a separate receptacle, or one column composed of a number of tubes 2 may have 105

a single coin receiver. For this purpose we have shown a closed tube 12, Fig. 1, which may be inserted in the strap 5 at the lower end of a tube 2 and suitably locked in position.

Strips of moldings 13 are placed over the wings and screws on the straps 5, so as to prevent their being removed except when necessary.

10 Having thus described our invention, what we claim and desire to secure by Letters Patent is—

1. The combination in a door having a coin-controlled lock and a coin chute, of a hollow hinge therefor, with the interior of which the coin chute connects.

2. The combination with a door, of a hollow tubular hinge having a divergent coin chute connecting with the interior of the tube.

3. The combination of a series of doors placed one above the other, each door having a hollow hinge, and the hollow hinges in line and communicating with one another to serve as 25 to serve as a coin receptacle or chute.

4. The combination of a series of doors placed one above the other, each door having a hollow hinge, the hollow hinges in line and communicating with one another to serve as 30 a coin receptacle, and said doors each having coin chutes intersecting and discharging into said hollow hinges.

5. The combination with a door, of a hinge consisting of a tube open at the ends and carried by the door, a fixed support, and straps secured to said support in which the ends of said tube turn, and said door having a coin chute intersecting the interior of said tubular hinge.

40 6. The combination with a door, of a hinge consisting of a tube open at the ends and carried by the door, a fixed support, straps secured to said support in which the ends of said tube turn, said door having a

coin chute intersecting the interior of said 45 tubular hinge, said straps having inwardly projecting, segmental ribs which abut the ends of the tube and form stops to limit the endwise movement of the tube, and other doors having similar tubular hinges journaling in these self-same straps.

7. The combination of a series of doors one above the other, each having a tubular hinge open at the ends, each of said doors having a coin chute leading into the tubular 55 hinge, all of said tubular hinges being in line, a fixed support, and straps secured to said fixed support and embracing the adjacent ends of said tubular hinges.

8. The combination of a series of doors 60 one above the other, each having a tubular hinge open at the ends, each of said doors having a coin chute leading into the tubular hinge and all of said tubular hinges being in 65 line, a fixed support, and straps secured to said fixed support and embracing the adjacent ends of said tubular hinges, said straps having inwardly projecting parting beads between the hinges and supporting the latter endwise.

9. The combination of a series of doors one above the other, each having a tubular hinge open at the ends, all of said tubular 70 hinges in line, a fixed support, and straps secured to said fixed support and embracing 75 the adjacent ends of said tubular hinges, said doors having coin chutes intersecting their respective tubular hinges, and each door and hinge being turnable independently of the other doors.

In testimony whereof we have hereunto set our hands in the presence of two subscribing witnesses.

WILLIS S. FARNSWORTH.
WILLIAM H. REED.
